TELEPHONE INDEX OR THE LIKE

William S. Sherman, Chicago, Ill., assignor to Coy Corporation, Chicago, Ill., a corporation of Delaware

Filed May 22, 1961, Ser. No. 65,275

Term of patent 14 years

(Cl. D74—1)

FIG. 1 is a top plan view of a telephone index or the like, embodying my new design;

FIG. 2 is a side elevational view thereof, the side opposite thereto being similar in appearance;

FIG. 3 is a front elevational view of the same but on a slightly reduced scale; and

FIG. 4 is a rear elevational view thereof also on a reduced scale.

I claim:

The ornamental design for a telephone index or the like, substantially as shown and described.
